LUDOVIC GLÜCK, OF ARAD, RUMANIA

SAFETY DEVICE FOR CONTAINERS HOLDING LIQUIDS WHICH DEVELOP EXPLOSIVE GASES

Application filed June 1, 1928, Serial No. 282,157, and in Hungary June 4, 1927.

The safety devices hitherto in use secured safety against explosions as a rule only during the period of filling the container. These devices were perforated cylindrical tubes provided with a bottom and a double wall, the tubes being inserted into the container and, after the latter had been filled, sealed by means of a solid cover or with a plug. In the latter case, a further protecting cover was used. Once the safety filling tubes had been sealed, the containers were by no means rendered safe, for example, during conveyance or when stored, since in case of fire the excess pressure of the gases which were developed burst the containers and an explosion ensued.

Experiments have also been made with devices in which at a certain temperature the seal is fused, but these devices are of a complicated design and, moreover, on the one hand they are not reliable and, on the other hand, after the seal had fused special work which, however, it was not always possible to execute, was necessary in order to put the seal right again; in such cases the containers were merely solidly sealed again.

The object of the present invention is the production of a safety device which provides complete security against explosions for containers holding liquids which develop gases even should the containers be exposed to fire. Further, the present invention effects an improvement in the familiar filling tube, or filling liner.

Accordingly and in accordance with the present invention the filling liner is used with an outlet-sealing liner which consists of a lower part that comprises the outlet and is provided with a sealing valve; the gases owing to their excess pressure lift the sealing valve and can then escape through the sealing liner; further, in accordance with the present invention, the filling liner consists of two special perforated hollow bodies inserted one within the other, and maintained in relative position.

Three forms of the device comprising the subject matter of the present invention are shown by way of example in the accompanying drawings.

Fig. 1 is partly an elevational view and partly a section of the first form of invention.

Fig. 2 is a vertical section through the centre of same.

Fig. 3 is a vertical section through the centre of the second form of invention.

Fig. 4 is partly a view and partly a section of the third form of invention.

In the first form of construction, into the open metal cylinder 1 Fig. 1 is inserted the open metal cylinder 2 Fig. 2 which is held and fixed in the cylinder 1 by means of the groove 3 which is subsequently pressed in. The jacket of the cylinder 1 Fig. 1 lying below the groove 3 is provided with oblique incisions 1^a directed from outside inwards, but the bottom of the jacket is provided with fine perforations 1^b. The spirally shaped jacket of the cylinder 2 is provided along the spirals with triangular holes 2^a likewise directed from outside inwards, but the holes 2^b in the bottom of the jacket are of a circular shape; the unperforated spiral shaped herring bone edge of the jacket constitutes a stiffening rib. The cylinders 1 and 2 constitute the filling liner.

The open upper end of the cylinder 1 is provided above the groove 3 with an outer screw thread 1^c by means of which the entire safety device can be screwed into the container, not shown in the drawings. Further, the upper open end of the cylinder 1 is also provided with inner threads 1^a Fig. 2 into which the outlet-sealing filler designated as a whole by 25 is screwed.

The lower portion of this sealing filler, the hollow screw 4, is screwed by means of its outer thread 4^a, as previously described, into the inner thread 1^d on the cylinder 1; the hexagonal head of the hollow screw 4 facilitates the screwing of the entire safety device into the container, and after this has been screwed on the hexagonal head completely seals the inlet opening in the container and lies against the wall of the container. The hollow screw 4 is formed internally as a valve seat 5 the circular opening 6 of which is sealed by the ball valve 7. The valve is loaded by a spring 8 which is pressed against the ball valve 7 by the cap screw 9 which

forms the upper portion of the sealing liner and is provided with openings; the cap screw is screwed into the inner screw thread of the hollow screw 4. The hollow screw 4 is further provided below the valve seat with the perforated metal basket 10.

The safety device is mounted and its effect is as follows:

The ball valve 7 is placed over the opening 6 of the valve seat provided in the hollow screw 4. The spring 8 is placed on the ball valve 7, then the screw cap 9 is screwed on to the inner screw thread of the hollow screw 4, whereby the cap screw 9 presses the spring 8 against the ball valve 7, so that the ball valve seats on the valve seat 5 and completely seals the opening 6. The outlet sealing liner 25 assembled in this way is screwed into the inner screw thread 1^a provided in the upper open end of the cylinder 1 of the filling liner. The safety device put together in this way is inserted into the container through its inlet opening and suitably fastened therein.

When the container is being filled, the outlet-sealing liner is unscrewed from the filling liner. In the event of the gases becoming ignited, an explosion is prevented in the familiar way owing to the perforated surfaces of the filling liner.

If for any reason an excess pressure should ensue after the outlet-sealing liner has been screwed into the filling liner, then the gases penetrating through the perforated metal basket 10 will overcome the effect of the spring 8, will lift the ball valve 7 and escape through the opening 6 as also through the cap screw 9. Should these gases, however, become ignited on the outside of the device then the conflagration will not extend even as far as the filling liner, because the perforated metal basket 10 blocks the path of the flames.

The second form of construction Fig. 3 is more particularly suitable for retail containers. In this case the filling liner is formed by the perforated metal baskets 11 and 12, which can be soldered together at their upper open ends. The outlet-sealing liner is designed as a double valve. The cone shaped lower valve seat 13 of which is provided with holes 13^a and is secured to the container; co-operating with this valve seat is the gas valve 14 which opens upwards and is lifted by the gases when there is any excess pressure. The gas valve 14 serves simultaneously as a seat for the liquid valve 15 which opens downwards and is pressed down on to its seat by the spring 16. The valve rod 17 serves the purpose of a guide for the valves 14 and 15. For the sake of clarity the valve 14 as also the valve 15 are shown in the open position.

If the container is being filled with the aid of a funnel, then the weight of the liquid that is poured on to the sealing filler over-

comes the tension of the spring 16, the liquid valve 15 opens downwards and the liquid passes through the openings 18 in the gas valve 14 which is now in the closed position, then through the lower openings 13^a in the valve seat 13 into the filling liner and from thence into the container. Except when the container is being filled, the liquid valve 15 is always pressed against the seat formed by the valve 14.

In the third form of construction as shown at Fig. 4, which is suitable mainly for smaller containers, the filling liner is identical with that shown in the first form of construction Fig. 1, with the difference, nevertheless, that in this case Fig. 4 the metal cylinders 1^x and 2^x are not joined together by means of a groove, but by having their upper open ends soldered together. The ball valve 7^x lies owing to its own dead weight on the valve seat 19 formed in the sealing liner. If owing to excess pressure the ball valve 7^x is lifted, then the gases flow through the now released openings in the valve seat 19 and escape through the lateral openings 20.

Since in this form of construction the ball valve 7^x is not loaded, it will come into action even when there is a very slight increase in the temperature of the gases.

Within the limits of their design and effect also the characteristics of the present invention can be freely modified, without the invention itself suffering any modification thereby.

Thus for example the shape, material and dimensions of the filling liner and of the sealing liner can be selected so as to suit any requirements existing from time to time.

It is preferable to produce the device by a cold process, and to avoid any soldering and thus to enhance considerably the safety in working.

The filling liner can also be constructed preferably in such a way that same can neither drop into the container nor can it be removed therefrom and so as to be inaccessible. Should the accessible cylinder 2 be injured in any way, the cylinder 1 will still afford ample security.

Between the outer and the inner hollow body of the filling liner one or two distance pieces can be arranged, for example, a wire running along between them. The openings in the outer hollow body end in edges which are turned inwards and which are constructed in such a way that they cannot be penetrated by the flames. Owing to the ribbed formation of the inner hollow body, any heat that is set up is distributed over a fairly large surface. The perforations in the inner hollow body can be arranged anywhere on the lower portion of the rib; the great advantage of the triangular perforation is to be found in the fact that any flames which may arise are split up into three portions.

The openings in the outlet surfaces are not conditional to the shape and to the method of construction of the described openings.

What I claim as my invention and desire to secure by Letters Patent is:—

5 1. A safety closure for pressure storage containers, comprising a pair of perforated members, one nested within the other, one of the members having its side walls formed in spiral grooves and ridges with incisions driven inwardly, and a yieldably mounted valve for the closure to relieve pressure above a certain amount from the container.

10 2. A safety closure for pressure storage containers, comprising perforated baskets nested one within the other, and connected at their open ends, the perforations of one of said baskets being triangularly shaped incisions driven inwardly, and valve means for 15 the open ends of the baskets to open under excess pressure from the interior of the container.

In testimony whereof I hereunto affix my signature.
